(No Model.)

B. B. USSHER.

SHAWL STRAP.

No. 538,988.

Patented May 7, 1895.

UNITED STATES PATENT OFFICE.

BRANDRAM B. USSHER, OF KANSAS CITY, MISSOURI.

SHAWL-STRAP.

SPECIFICATION forming part of Letters Patent No. 538,988, dated May 7, 1895.

Application filed August 10, 1894. Serial No. 519,936. (No model.)

To all whom it may concern:

Be it known that I, BRANDRAM B. USSHER, of Kansas City, in the county of Jackson and State of Missouri, have invented certain new and useful Improvements in Shawl-Straps, of which the following is a full, clear, and exact description, reference being had to the accompanying drawings, which form a part of this specification.

10 My invention relates to certain new and useful improvements in shawl straps, and the object of my invention is to provide a shawl strap which may be used with an extended strap to pass around large bundles or, as a 15 double strap, to pass twice around smaller bundles or, as a double strap to pass around a bundle over two dimensions thereof, and also to provide in combination therewith smaller straps by which to attach small bundles to the large bundle and carry the same therewith; and my invention consists in certain features of novelty hereinafter described and pointed out in the claim.

Figure I represents my improved shawl- 25 strap as an extended strap adapted to pass around a large bundle. Fig. II represents my improved shawl-strap as a double strap adapted to pass twice around the smaller bundle, showing also the short strap for carrying small bundles in the same package. Fig. III represents my improved shawl-strap as adapted to pass around smaller bundles over two dimensions thereof. Fig. IV represents one means by which the short strap may be 30 secured to the main strap.

Similar numerals refer to similar parts throughout the several views.

1 represents the handle formed as in the ordinary shawl strap. To one end of the handle is attached the ordinary buckle 2, and to the buckle is attached the strap 3 provided with the sliding keeper 4. To the other end of the handle is attached the buckle having a ring 5 provided with the two tongues 6 and 7 40 one of said tongues being connected with the handle by the opening 8 therein and the other tongue being connected with the strap 10 attached to the buckle, by the opening 9 therein. By this buckle the strap is adapted to be used 45 as a double strap as shown in Fig. III, the strap 3 passing around the handle in one direction and engaging the tongue 6, and the

strap 10 passing around the handle at right angles thereto and engaging the tongue 7. The strap 10 is provided at its other end with 55 the buckle 11 and carries on it the sliding keeper 12.

13, 14 represent the short straps, when not in use carried under the keepers represented by 15 and 16. When in use said straps are 60 withdrawn from the keepers and passed through the buckles 2 and 5 as shown in Fig. II. I would not however limit myself to this means of attaching the auxiliary straps as they may be attached as shown in Fig. IV by 65 stitching to the main strap as shown at 17 and passing the free end under the keepers 18.

19 represents a plate on the handle for a name and address.

In use, my improved shawl strap presents 70 the greatest convenience. When used as a single extended strap as shown in Fig. I the strap 3 is engaged at the buckle 11. When used as a double strap as shown in Fig. II the strap 3 is passed around the bundle and engaged 75 with its buckle 2 and the strap 10 is also passed around the bundle and engaged with its buckle 5, the buckle 11 being passed through the buckle 5. It may also be used as a double strap as shown in Fig. III the 80 strap 3 being passed around the bundle and engaging one of the tongues of the buckle 5 and the strap 10 passed at right angles to the strap 3 around the bundle and engaged with the other tongue of the buckle 5 thus making 85 a neat, compact and safe fastening for the bundle, and presenting one of the principal advantages of my improved shawl strap.

Having thus fully described my improvements, what I claim as my invention, and desire to secure by Letters Patent, is—

A shawl strap comprising the buckle consisting of the ring 5 and the tongues 6 and 7, a handle secured to said buckle and connected with the tongue 6, a strap 3 connected with 90 the handle, and a strap 10 secured to the buckle and connected with the tongue 7, and a buckle 11 on the end of the strap 10 substantially as shown and described and for the purpose set forth.

BRANDRAM B. USSHER.
